[57] CLAIM

The ornamental design for a surgical bariatric trocar tip, substantially as shown and described.

DESCRIPTION

FIG. 1 is a top front perspective view of a surgical bariatric trocar tip showing our new design, without the pigtail thread;

FIG. 2 is a top plan view thereof;

FIG. 3 is a bottom plan view thereof;

FIG. 4 is a front elevational view thereof;

FIG. 5 is a cross-sectional view taken along line 5—5 of FIG. 2;

FIG. 6 is a front elevational view thereof having a pigtail thread attached thereto and wound thereon; and

FIG. 7 is a perspective view thereof showing the pigtail thread in an unwound position.
